ELECTRIC APPLIANCE FOR COOKING SAND- WICHES, COOKIES, PASTRIES AND OTHER FOOD ARTICLES

Ross E. Cornwell, Chicago, Ill., assignor to Sunbeam Corporation, Chicago, Ill., a corporation of Illinois

Filed Apr. 6, 1961, Ser. No. 64,636

Term of patent 14 years

(Cl. D81—10)

FIG. 1 is a perspective view of an electric appliance for cooking sandwiches, cookies, pastries and other food articles showing my new design;

FIG. 2 is a side elevational view thereof;

FIG. 3 is a rear elevational view thereof; and

FIG. 4 is a top plan view thereof.

The dominant features of my design reside in the portion shown in full lines.

I claim:

The ornamental design for an electric appliance for cooking sandwiches, cookies, pastries and other food articles, substantially as shown and described.
